GAS BOTTLE RACK FOR TRAILERS

Leo B. Obenchain, Branford, Conn.

Original application May 14, 1948, Serial No. 27,010. Divided and this application June 15, 1951, Serial No. 231,883

3 Claims. (Cl. 312—100)

1

This application is a division of my application Serial No. 27,010, filed May 14, 1948, now forfeited, and has to do with an invention relating to a support for gas bottles.

An object of the present invention is to provide a support for gas bottles which is suitable for mounting on a trailer and which includes a means for locking the bottles in position to prevent removal thereof.

Another object of the invention is to provide a support for gas bottles which is simple in construction, and easy to install upon a trailer.

Further objects and advantages of the invention will become apparent from the following description and claims, and from the accompanying drawing, wherein:

Figure 1 is a perspective view with parts broken away in section, of the forward portion of a trailer coach provided with a gas bottle supporting structure according to the present invention and showing a pair of gas bottles mounted thereon.

Figure 2 is a top plan view of the gas bottle supporting structure according to the present invention.

Figure 3 is an enlarged fragmentary cross-sectional detail view taken on the line 3—3 of Figure 2.

Referring to the drawing, 11 designates a conventional trailer coach having the usual front tongue structure 12. Bolted to the tongue 12 is a horizontal base plate 13 to which is rigidly secured the spaced annular upstanding ring members 14, 14 adapted to receive the annular bottom flanges 15 of a pair of conventional gas bottles 16, 16 as shown in Figure 1. The gas bottles are provided with the usual top neck portions 17, 17. The base plate 13 may be secured to the tongue structure 12 by means of any fastening means, not shown.

Secured to the base plate 13 intermediate the ring members 14, 14 is an upstanding vertical bar member 19 which is formed adjacent its top end with a rearwardly extending horizontal arm 20. Overlying the bottle neck portions 17, 17 of the bottles 16, 16 is a flanged top cover member 21 which is provided with a slot 22 through which projects an upstanding apertured tab 23 formed on the top end of the bar member 19. The top cover member 21 has secured to the inside surface of its rear depending flange portion a connecting means or vertical channel bracket 24, each side flange of said bracket being formed with a vertical slot 25. The end of the arm 20 is received between the flanges of bracket 24 and secured

2

to said end is a transverse pin 26 whose ends are slidably received in the vertical slots 25 of said flanges. A diagonal brace bar 32 connects the end of arm 20 with bar member 19, increasing the rigidity of said arm with respect to said bar. To lock the cover member 21 against upward movement, the hasp of a suitable padlock 28 may be engaged in the aperture 29 of the tab 23. To lift the cover member 21, padlock 28 is removed and the cover member may then be raised, the slots 25 allowing the cover member to be raised sufficiently to release the depending peripheral flange of the cover member from engagement with the bottle neck portions 17, 17 of the gas bottles 16, 16 mounted on the ring members 14, 14 of the plate member 13.

I claim:

1. A support for gas bottles comprising a base plate, a plurality of ring members secured to said base plate and each adapted to receive the base flange of a gas bottle, an upstanding bar member secured to said base plate, a horizontal arm positioned adjacent the upper end of said bar member and having one end secured to said bar member, a cover member provided with a depending peripheral flange positioned above said horizontal arm, there being an opening in said cover member slidably receiving the upper end of said bar member, said cover member being adapted to be placed over the top ends of the neck portions of gas bottles when positioned in said ring members, and a connecting means dependently carried by said cover member and slidably receiving the other end of said arm.
2. A support for gas bottles comprising a base plate, a plurality of ring members secured to said base plate and each adapted to receive the base flange of a gas bottle, an upstanding bar member secured to said base plate, a horizontal arm positioned adjacent the upper end of said bar member and having one end secured to said bar member, a cover member provided with a depending peripheral flange positioned above said horizontal arm, there being an opening in said cover member slidably receiving the upper end of said bar member, said cover member being adapted to be placed over the top ends of the neck portions of gas bottles when positioned in said ring members, a horizontally disposed pin carried by the other end of said arm, and a bracket dependently carried by said cover member and slidably receiving said pin.
3. A support for gas bottles comprising a base plate, a plurality of ring members secured to said base plate adapted to receive the base flanges of

the gas bottles, a vertical upstanding bar member secured to said base plate, a cover member provided with a depending peripheral flange, said cover member being adapted to be placed over the top ends of the neck portions of the bottles and being formed with an opening, an apertured tab carried at the top end of said bar member and projecting through said opening, a horizontal arm carried by the upper portion of said bar member, a hinge pin secured to the end of said arm, and a channel shaped bracket secured to said cover member and receiving the end of said arm, the sides of said bracket being formed with

5

vertical slots slidably receiving the ends of said hinge pin.

LEO B. OBENCHAIN.
